UNITED STATES PATENT OFFICE

EUGENE P. MILES, OF HOBART, OKLAHOMA, ASSIGNOR TO BERNICE VIRGINIA MILES,
OF OKLAHOMA CITY, OKLAHOMA

APPARATUS FOR REGULATING TEMPERATURES IN BUILDINGS

Application filed October 5, 1931. Serial No. 567,080.

This invention relates to apparatus for regulating temperatures in buildings and it is more especially an improvement upon the apparatus disclosed in my Patents 1,681,995 of August 28, 1928, and 1,649,037 of November 15, 1927.

It is an object of the present invention to combine an air cleaning and cooling apparatus with a heating means so that during warm weather cool clean air can be supplied to the building through conduits and flues which, at other times, are employed for distributing heated air.

Another object is to utilize a supplemental air supply for furnishing heated filtered air to the interior of the building in which a circulation of warm air is taking place.

A further object is to filter fresh air and cool it by a simple and effective means which is accessible readily for cleaning and repairs.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings:

Figure 1 is an outside elevation of the structure containing the heating and cooling units.

Figure 2 is a section on line 2-2, Figure 1.

Figure 3 is an enlarged section on line 3-3, Figure 1.

Figure 4 is a section on line 4-4, Figure 3.

Figure 5 is a diagram showing a floor plan of a building containing the present improvements.

Figure 6 is an elevation of one of the panels of the cooling system its holding means being in section.

Figure 7 is an enlarged section on line 7-7, Figure 6.

Referring to the figures by characters of reference, 1 designates a chimney structure containing a flue 2 and formed in this structure at the sides of the flue but out of communication therewith are cooling chambers 3 each of which has an outside door 4 whereby access thereto may be had readily.

A mantel 5 is erected in the building A across the inner side of chimney 1 and is provided in its top with the grating 6 through which the flow of air can be controlled by pivoted slats 7 operated by any suitable means.

An air box 8 is located below the floor level 9 and beneath a fire box or combustion chamber 10 built into the mantel. This fire box has a grate 11 for supporting fuel and an air inlet 12 having a damper 13, supplies air beneath the grate to support combustion. The front of the fire box can be closed by a door or the like indicated generally at 14 and which can be like that shown in my Patent 1,681,995.

Spaced outlet flues 15 are inclined upwardly from the fire box to the flue 2 in chimney 1 and are provided with dampers 16 adapted to be opened or closed by a rod 17. An inlet for air can be provided in the front of the mantel above the fire box as at 18 and has a series of dampers 19 for controlling the flow. This allows air from the room to be reheated and then delivered through grating 6.

The air box 8 opens upwardly into an air chamber 20 which extends across the back, sides and top of the fire box but is out of communication therewith. Thus fuel burned on the grate will heat air in chamber 20 from which it can escape through the outlet 6 into the adjacent room B in the building A. The floor of this room contains an outlet grating 21 opening into an air flue 22 which leads to the air box 8. These gratings 21 and 23 can be of the usual type for use with air heating systems, there being dampers shiftable by foot or otherwise by means of which the gratings can be opened or closed to control the free flow of air through the several rooms. In cold weather the gratings can be regulated

to cause warm air to flow to any room or rooms desired while in warm weather the gratings can be regulated to cause desired rooms to be cooled. As the several rooms 5 communicate through door openings 25 and through wall gratings 26 a circulation of warm air through the entire structure can be effected.

Water containers 27 can be located in the 10 sides of the mantel for supplying moisture to the air being heated. These are kept filled by float controlled water inlet valves 27'.

The structure thus far described does not 15 differ greatly from that already patented by me. The present improvements include a means for filtering and heating fresh air to be supplied to the building to mix with the circulating air, and a means for filtering and cooling fresh air to be supplied to 20 the building.

The fresh air heating means includes a metal flue 28 supported in the flue 2 and having an outside air inlet 29 and an inside air outlet 30. At the inlet there is provided a grating 31 back of which is provided a screen 32. A mineral wool or other filtering material 33 is interposed between the grating and screen and is supplied with 25 an oil or other suitable fluid, through apertures formed in the bottom of a reservoir 34. A trough 35 is located beneath the filtering material for receiving the fluid draining therefrom and this can have an outlet 30 36 leading to a sewer.

The outlet 30 is located near the ceiling of the room B and can be partly or entirely closed by a damper 37. Another damper 38 can be located in flue 28 and operated by a 40 rod 39 and lever and rod connections 40 and 41 as shown.

Vitiated air can be vented into the chimney through an outlet 42 having a damper 43.

45 For the purpose of supplying cool clean air to the rooms of the building A, each of the air cooling chambers 3 is provided. These chambers open near their lower ends through outlets 44 into the air box 8 and 50 are also provided near their lower ends in their outer walls with inlets 45 for fresh air. Each inlet can have a damper 46 for controlling the flow of air therethrough. The bottom of each chamber 3 is formed of 55 a deep water pan 47 having an overflow 48 near the top thereof opening into a pipe 49 leading to a sewer or other outlet.

Each compartment is divided by a central partition 50 into an inlet side 51 and 60 an outlet side 52 both of which communicate through a top or intermediate chamber 53. The lower end of the partition 50 extends below the level of water in pan 47 so that air can flow from the inlet 45 to 65 outlet 44 solely by way of the portions 51

and 52 of the compartment and the intermediate chamber 53.

Upper and lower pairs of parallel angle strips 54 are secured in chamber 3 and engage and support the corner portions of 70 frames 55 each of which is wrapped with a thin fabric 56 such as gauze. Clips 57 grip the fabrics to the tops of the frames and said frames are held assembled at proper distances by rods 58 extending 75 therethrough and having spacing sleeves 59 or the like.

A spraying head 60 is supported in chamber 80 53 and is supplied with water under pressure so that a mist will be produced in said chamber in the path of the current of air flowing to the outlet 44.

For the purpose of producing a forced draft of either warmed or cooled air, a reversible motor driven fan 61 of any desired construction is located in the flue 22 leading to box 8. While the building is being heated this fan can be operated to suck air through the heater into the rooms as already explained. During the heating operation the dampers 46 and 62 are closed and water is not delivered from the spraying head 60.

When it is desired to cool the building A during warm weather water is sprayed 95 from heads 60, dampers 46 and 62 are opened, dampers 7 and 19 are closed, and fan 61 is actuated to draw air from the inlets 45 through compartments 3 to outlets 44 and then into flue 22 from which 100 it is distributed to the several floor grates. The water delivered from heads 60 will saturate the panels formed by frames 55 and their fabric coverings and as the air must flow along the panels and through the mist in chamber 53 it will be quickly and effectively cooled before it enters box 8. The used air can leave the building through outlet 42 or any other desired place.

Dampers 62 are provided for controlling 110 the flow of filtered air through the outlets 44, these dampers being operated by rods 63 or the like.

For the purpose of supplying chilled air 115 to the rooms supplemental cooling means can be provided in the form of mechanical refrigerating units 64 supported in the spaces in the side portions of the mantel structure. Thus air circulating through the mantel can be chilled to a desired temperature.

In the structure described filtering and cooling apparatus is built into the building adjacent to the chimney if desired, however, it can be located outside of and separated 125 from the building in which event it will be connected to air box 8 by a suitable conduit or flue in any obvious manner.

The present apparatus serves to remove 130 moisture from the air brought into the build-

ing; to remove dust and disease-carrying germs from the air brought into the house during the winter months; and warms the fresh air during the winter months after it ⁵ has been filtered and before it is delivered into the house.

What is claimed is:

1. Apparatus of the class described including an air flue, a reversible air forcing element in the flue, an air box opening into the flue, means for heating air in said box, air cooling means opening into said box and separate means for controlling the flow of air through both of said means, said air cooling ¹⁰ means including a chamber having an air inlet and an outlet, said outlet opening into the air box, spaced fabric covered panels supported between the inlet and outlet, water spraying means above the panels for ¹⁵ saturating them, means for directing the flow of air between and along the panels while traveling from the inlet to the outlet, comprising a partition dividing the panel containing chamber into an inlet side and ²⁰ an outlet side, and a water pan into which the lower end of the partition extends.

2. Apparatus of the class described including a compartment having an air inlet and air outlet, an imperforate partition ³⁰ therebetween, a water pan into which the lower end of the partition extends to prevent passage of air under the partition, panels at opposite sides of the partition each comprising a frame, a fabric wrapped about ³⁵ the frame and clips for clamping the fabric to one end of the frame, supporting strips for the panels, supporting means extending through the panels, means on said supporting means for holding the panels in spaced ⁴⁰ relation, and means for spraying water onto the panels.

3. In a building structure, a chimney flue in communication therewith, a damper for controlling the flow of air from said structure ⁴⁵ into the chimney flue, a main air flue leading from the floor of said structure to the chimney flue, a grating for controlling the flow of air between the main air flue and the interior of said structure, a heater ⁵⁰ for air, air-cooling means, a fresh air flue opening into the structure from without, an air filter therein, a damper for said flue, and means operating in the main flue for forcing a circulation of air within the fresh air flue, ⁵⁵ filter and structure in one direction and through the air cooling means and structure to the chimney flue in the opposite direction.

In testimony that I claim the foregoing as my own, I have hereto affixed my signature.

EUGENE P. MILES.
